MEANS FOR INSTALLING SUBSURFACE TOOLS

Harry B. Schramm, deceased, late of Dallas, Tex., by
Josephine Schramm, executrix, Dallas, Tex., assignor to
Otis Engineering Corporation, a corporation of Texas

Filed June 30, 1958, Ser. No. 745,687

11 Claims. (Cl. 166—218)

This invention relates to means for installing subsurface tools in an oil well tubing string and, more particularly, to such means which are pre-set at the surface of the well, which bias the longitudinal axis of the tool to be installed from the longitudinal axis of the tubing string when the tools and means are inserted in the tubing string and which, without the use of other equipment, direct the tool into an offset pocket in the tubing string as the tool approaches the entrance to the offset pocket during its downward travel in the tubing string.

A principal object of this invention is to provide means for installing tools in an offset pocket in a tubing string, which means are pre-set at the surface of the well so that it will direct a tool into the desired offset pocket without the necessity for any other type of equipment other than conventional wire line equipment.

Another object is to provide such means which cooperate with the peculiarly internally configured tubing string to so install the tool in the desired offset pocket.

A further object is to provide such means which, when pre-set, will select the desired offset pocket from a number of such offset pockets located at vertically spaced apart positions in the tubing string in which to install the tool.

Other objects and advantages will become apparent in the course of the following detailed description.

In the drawings, forming a part of this application, and in which like parts are designated by like reference numerals throughout the same,

Fig. 1 is an elevational sectional view illustrating the installing of a valve in a preselected offset mandrel pocket.

Fig. 2 is an enlarged sectional view of the valve installing means illustrated in Fig. 1.

Fig. 3 is a perspective view of the guide shoe employed in the mandrel of Fig. 1.

Fig. 4 is a sectional view taken on line 4—4 of Fig. 1, with the installing means removed from the mandrel.

Figs. 5, 6 and 7 are views similar to Fig. 4 illustrating the manner by which preselected mandrels may have valves installed therein.

While the means of this invention can be employed to install various types of tools in and laterally off-center of an oil well tubing string, it is described herein in use with a gas lift valve and an offset mandrel having an offset pocket in which the valve is to be installed, as shown in Fig. 1.

Referring now to the drawings, the offset mandrel 10 may be one of the conventional types adapted to be made up in a tubing string 11, and has a main bore 12 in line with the main bore of the tubing string and has a side pocket 13 offset from the main bore 12. The offset mandrel is provided with a guide shoe 14 inserted in the upper portion of the mandrel and integrally connected therewith. The guide shoe 14 is, in effect, a fixed cylindrical sleeve within the upper end of the main bore 12 coaxially therewith, and has downwardly sloped upper cam surfaces 15 and 16 commencing at the apex point 17 and extending downwardly to the slot 18 which has a

2

depth equal to the thickness of the sleeve and which extends downwardly to the lower end of the shoe. The location of the slot 18 with respect to the offset pocket 13 is an important aspect of this invention, as is more fully explained hereinafter.

The installing tool 20 comprises a mandrel 21 having a longitudinal bore 22 laterally off-center of the central axis of the mandrel and opposite the pin 23. Spring 24 within the bore forces the plunger 25 downwardly against the upper end 26 of the eccentric connector 27. Since the connector neck 28 is eccentrically connected to the mandrel by the pin 23, the downward force exerted on the connector neck 28 by the plunger 25 tends to cause the eccentric connector to pivot about the pin 23. Of course, the eccentric connector will not pivot about the pin if it is restrained from such movement by the walls of the tubing or the guide shoe.

The mandrel 20 also contains a radial bore 30 perpendicular to its longitudinal axis. Locator key 31 is maintained in this bore by pin 32 which passes through the mandrel and through the elongated slot 33 in the locator key and is constantly urged outwardly by spring 34. The lengthwise axis of the locator key flange 35 is parallel to the slot 18 of the guide shoe, and the width 25 of the flange is less than the width of the slot 18. Hence, it will be seen that as the installing tool 20 moves downwardly towards the offset mandrel 10, the locator key will ride along the internal wall of the tubing string. Next, the locator key will be forced toward the slot 18 30 when it comes in contact with either guide shoe surface 15 or 16 so that the external flange of the locator key will slide downwardly into and through the slot 18 as the mandrel passes through the guide shoe. As the mandrel 20 is rotated by the coaction of the locator key 31 35 and the guide shoe surfaces 15 or 16, the eccentric connector 27 is oriented in such manner as to point toward the offset pocket 13.

A second mandrel 20 may be provided in which the locator key bore 30 is rotated 90° about the central axis 40 of the mandrel 21. In this case, the locator key 31 when disposed within the slot 18 would cause the eccentric connector 27 to be directed at an angle 90° from that shown in Fig. 1. However, should the guide shoe 14 be also rotated 90° in mandrel 10, as illustrated in Fig. 45, in the direction which the new bore 30 is rotated, the eccentric connector 27 would be directed as shown in Fig. 1 when the locator key is disposed within the slot 18. Similar results can be obtained by providing additional mandrels in which the locator key bore 30 is disposed 50 at additional angles such as 180° and 270° to that shown in Fig. 1, such modifications being illustrated in Figs. 6 and 7. It is important to observe that when the bore 30 is rotated a specified number of degrees in a given direction, the eccentric connector will be directed towards 55 the offset pocket, as shown in Fig. 1, only when the guide shoe 14 is rotated an equal number of degrees in the same direction.

In operation, the means of this invention may be employed to install tools in a number of offset mandrels 10 60 made up in an oil well tubing string. By way of illustration, it will be assumed that the tubing string 11 contains five offset mandrels, as shown in Fig. 1, connected in the tubing string 11 at predetermined elevations, with the first and fifth (uppermost and lowermost) each having a guide shoe 14 disposed therein, as shown in Fig. 1, and with the second, third and fourth each having a guide shoe rotated therein by 90, 180 and 270°, respectively, as 65 shown in Figs. 5, 6 and 7. In this situation, four installing tool mandrels 20 will be required to install a tool in each of the offset pockets. The first mandrel will be configured, as shown in Fig. 1, and will be employed 70

to install a tool in the first and fifth offset pockets. The second, third and fourth mandrels (not illustrated) will each have a locator key bore 30 rotated 90, 180 and 270°, respectively, in the same direction in which the guide shoes 14 of the second, third and fourth offset mandrels 10 were rotated.

After it has been determined in which offset pocket a tool, such as a conventional gas lift valve 36, is to be installed, the corresponding mandrel 20 is selected and made up in the conventional wire line by threaded engagement at 37. An eccentric connector 27 is attached to the running tool 38, and the flanged end 39 of the valve 36 is inserted in the running tool and connected thereto, as by tangential shear pins 41. After the eccentric connector 27 is connected to the mandrel 20 by pin 23, the entire assembly is lowered into the tubing string. If the valve 36 is to be installed in the first offset mandrel, the valve and eccentric connector will be directed toward the pocket 13 of the offset mandrel, as shown in Fig. 1, when the locator key flange 35 passes through the slot 18, as previously described. However, if it is desired to insert a valve in the third offset mandrel, the proper installing mandrel 20 will be used. When this mandrel passes through the first offset mandrel, the eccentric connector and the valve 36 will not be directed at the pocket 13 but in the opposite direction, and the tool will continue downwardly in the tubing string until the third offset mandrel is reached. At that time, the locator key will be directed in the direction opposite to that shown in Fig. 1, and will pass through the slot 18 of the guide shoe shown in Fig. 6, so that the eccentric connector will be directed toward the offset pocket, and the valve will enter the pocket as the mandrel 20 passes below the guide shoe of that offset mandrel. In like manner, a tool may be installed in the second and fourth offset mandrels merely by selecting the proper mandrel 20 in accordance with the particular mandrel 10 previously made up in the tubing string. It is to be noted, however, that a valve cannot be inserted in the fifth offset mandrel until one has been installed in the first offset mandrel. If a valve is installed in the first offset mandrel, and a second valve is run into the well using the same mandrel 20, the tool will be deflected from the offset pocket and will continue downwardly to the fifth offset mandrel.

If desired, the disadvantage described above of the lack of differentiation between the first and fifth offset mandrel can be overcome by the invention by increasing the length of the fifth offset mandrel to increase the distance between the guide shoe 14 and the upper end of the offset pocket 13 thereof. Then, when it is desired to install a valve in this offset mandrel, a longer running tool 38 is used so that the valve 36 will enter the pocket when the installing mandrel 20 is passing through the guide shoe slot 18. The valve 36 will not be inserted in the offset pocket of the first mandrel since the eccentric connector 27 will be constrained from rotation about pin 23 by the tubing string when the valve 36 is at the level of the top of the offset pocket. The same principle will apply if it is desired to differentiate between the second and a sixth offset mandrel 10 if each has the guide shoe slot 18 oriented in the same manner with respect to the offset pockets thereof.

After the valve has been installed in the offset pocket, the wire line is jarred upwardly, causing the tangential shear pins 41 to fail. Then, the entire assembly of wire line, mandrel 20, eccentric connector 27 and running tool 38 is retracted from the tubing string. When being retracted from the tubing string, should the locator key flange 35 not encounter the slot 18, it will be forced inwardly against the bias of spring 34 by contact between the upper key shoulder 42 which is sloped downwardly and outwardly, and the lower end 43 of the guide shoe 14, which is also sloped downwardly and outwardly.

In order to remove a valve from a given offset pocket,

the corresponding mandrel 20 is attached to the wire line at one end and to the eccentric connector 27 on the other end, to which is connected a conventional fishing tool (not shown) which can engage the flange 39 of the valve 36. The fishing tool must be of sufficient length to engage the flange 39 while the locator key 31 is still disposed in the slot 18. When the fishing tool contacts the valve 36, the wire line is jarred downwardly in a conventional manner until the fishing tool grips the flange 39. Now, the entire assembly of valve, fishing tool, eccentric connector, mandrel 20 and wire line is retracted in the conventional manner.

With this invention, it is to be observed that the force necessary to direct the valve toward the desired offset pocket is provided at the surface of the earth, that the force is longitudinally directed when in the well, and that no additional equipment of any type is required in the offset mandrel to so deflect the valve to be installed.

It is to be understood that the form of the invention, herewith shown and described, is to be taken as a preferred embodiment of the same, and that various changes in the shape, size and arrangement of parts may be resorted to without departing from the spirit of the invention or the scope of the attached claims.

Having thus described the invention, what is claimed and desired to secure by Letters Patent is:

1. Apparatus of the character described comprising an offset mandrel adapted to be connected in a tubing string, said offset mandrel having a vertical main bore extending therethrough, means forming an open topped, well tool receiving pocket within said offset mandrel, said pocket having its longitudinal axis offset from said main bore, a guide shoe comprising a cylindrical sleeve mounted in the upper end of said bore coaxially therewith, said sleeve having a longitudinal slot extending from the upper surface to the lower end thereof, the vertical plane determined by said slot and the main bore axis and the vertical plane determined by said offset pocket axis and said main bore axis being angularly related relative to one another by a predetermined angle, a running tool comprising an elongated mandrel adapted to pass longitudinally through said sleeve, a locator key extending radially outwardly from said running tool mandrel, said key being adapted to fit within said sleeve slot, an elongated connector member, means connecting the upper end of said connector member to the lower end of said running tool mandrel for pivotal movement of said connector member relative to said running tool mandrel in a single predetermined plane which includes the axis of said running tool mandrel, means on the lower end of said connector member for releasably engaging a well tool, said running tool mandrel and connector member having their axes in alignment at one relative position therebetween, and spring means acting between said running tool mandrel and connector member for normally biasing said connector member to pivot about said running tool mandrel in said predetermined plane to a position wherein said running tool mandrel and connector member axes are out of alignment, said predetermined plane and the plane defined by the running tool mandrel axis and the locator key being angularly related relative to one another by said predetermined angle of said offset mandrel.

2. Apparatus of the character described comprising an offset mandrel adapted to be connected in a tubing string, said offset mandrel having a vertical main bore extending therethrough, means forming an open topped, well tool receiving pocket within said offset mandrel, said pocket having its longitudinal axis offset from said main bore, a guide shoe comprising a cylindrical sleeve mounted in the upper end of said bore coaxially therewith, said sleeve having a longitudinal slot extending from the upper surface to the lower end thereof, said sleeve having its upper surface sloping upwardly from each side of said slot, the vertical plane determined by said slot and the

main bore axis and the vertical plane determined by said offset pocket axis and said main bore axis being angularly related relative to one another by a predetermined angle, a running tool comprising an elongated mandrel adapted to pass longitudinally through said sleeve and having a radial bore therein, a locator key disposed in said radial bore, spring means for urging said key radially outwardly from said running tool mandrel, said key having an outer vertical flange adapted to fit within said sleeve slot, said flange having a downwardly and outwardly sloping upper surface, an elongated connector member, means connecting the upper end of said connector member to the lower end of said running tool mandrel for pivotal movement of said connector member relative to said running tool mandrel in a single predetermined plane which includes the axis of said running tool mandrel, means on the lower end of said connector member for releasably engaging a well tool, said running tool mandrel and connector member having their axes in alignment at one relative position therebetween, and spring means acting between said running tool mandrel and connector member for normally biasing said connector member to pivot about said running tool mandrel in said predetermined plane to a position wherein said running tool mandrel and connector member axes are out of alignment, said predetermined plane and the plane defined by the running tool mandrel axis and the radial bore therein being angularly related relative to one another by said predetermined angle of said offset mandrel.

3. A well installation comprising a tubing string, a plurality of tubing mandrels connected at predetermined elevations in said tubing string, each tubing mandrel having a vertical main bore extending therethrough, means forming an open topped, well tool receiving pocket within said tubing mandrel, said pocket having its longitudinal axis offset from said main bore, and a guide shoe comprising a cylindrical sleeve mounted in the upper end of said bore coaxially therewith, said sleeve having a longitudinal slot extending therethrough from the upper surface to the lower end thereof, the vertical plane determined by said slot and the main bore axis and the vertical plane determined by said offset pocket axis and said main bore axis being angularly related relative to one another by a predetermined angle, and wherein said predetermined angle is different for each of said tubing mandrels.

4. A well installation comprising a tubing string, a plurality of tubing mandrels connected at predetermined elevations in said tubing string, each tubing mandrel having a vertical main bore therethrough, means forming an open topped, well tool receiving pocket within said tubing mandrel, said pocket having its longitudinal axis offset from said main bore, and a guide shoe comprising a cylindrical sleeve mounted in the upper end of said bore coaxially therewith, said sleeve having a longitudinal slot extending therethrough from the upper surface to the lower end thereof, said sleeve having its upper surface sloping upwardly from each side of said slot, the vertical plane determined by said slot and the main bore axis and the vertical plane determined by said offset pocket axis and said main bore axis being angularly related relative to one another by a predetermined angle, and wherein said predetermined angle is different for each of said tubing mandrels.

5. A well installation comprising a tubing string, a plurality of tubing mandrels connected at predetermined elevations in said tubing string, each tubing mandrel having a vertical main bore extending therethrough, means forming an open topped, well tool receiving pocket within said tubing mandrel, said pocket having its longitudinal axis offset from said main bore, a guide shoe comprising a cylindrical sleeve mounted in the upper end of said bore coaxially therewith, said sleeve having a longitudinal slot extending from the upper surface to the lower end thereof, the vertical plane determined by said slot and the

main bore axis and the vertical plane determined by said related relative to one another by a predetermined angle, and wherein said predetermined angle is different for each of said tubing mandrels, a running tool adapted to insert and remove a well tool in and from the offset pocket of a selected one of said tubing mandrels comprising an elongated mandrel adapted to pass longitudinally through the sleeve of said tubing mandrels, a locator key extending radially outwardly from said running tool mandrel and adapted to fit within said sleeve slot, an elongated connector member, means connecting the upper end of said connector member to the lower end of said running tool mandrel for pivotal movement of said connector member relative to said running tool mandrel in a single predetermined plane which includes the axis of said running tool mandrel, means on the lower end of said connector member for releasably engaging a well tool, said running tool mandrel and connector member having their axes in alignment at one relative position therebetween, and spring means acting between said running tool mandrel and connector member for normally biasing said connector member to pivot about said running tool mandrel in said predetermined plane to a position wherein said running tool mandrel and connector member axes are out of alignment, said predetermined plane and the plane defined by the running tool mandrel axis and said locator key being angularly related relative to one another at an angle corresponding to the predetermined angle of the selected one of said tubing mandrels.

30 6. A well installation comprising a tubing string, a plurality of tubing mandrels connected at predetermined elevations in said tubing string, each tubing mandrel having a vertical main bore extending therethrough, means forming an open topped, well tool receiving pocket within said tubing mandrel, said pocket having its longitudinal axis offset from said main bore, a guide shoe comprising a cylindrical sleeve mounted in the upper end of said bore coaxially therewith, said sleeve having a longitudinal slot extending from the upper surface to the lower end thereof, said sleeve having its upper surface sloping upwardly from each side of said slot, the vertical plane determined by said slot and the main bore axis and the vertical plane determined by said offset pocket axis and said main bore axis being angularly related relative to one another by a predetermined angle, and wherein said predetermined angle is different for each of said tubing mandrels, a running tool adapted to insert and remove a well tool from the offset pocket of a selected one of said tubing mandrels comprising an elongated mandrel adapted to pass longitudinally through the sleeve of said tubing mandrels and having a radial bore therein, a locator key disposed in said radial bore, spring means for urging said key radially outwardly from said running tool mandrel, said key having an outer vertical flange adapted to fit within said sleeve slot, said flange having a downwardly and outwardly sloping upper surface, an elongated connector member, means connecting the upper end of said connector member to the lower end of said running tool mandrel for pivotal movement of said connector member relative to said running tool mandrel in a single predetermined plane which includes the axis of said running tool mandrel, means on the lower end of said connector member for releasably engaging a well tool, said running tool mandrel and connector member having their axes in alignment at one relative position therebetween, and spring means acting between said running tool mandrel and connector member for normally biasing said connector member to pivot about said running tool mandrel in said predetermined plane to a position wherein said running tool mandrel and connector member axes are out of alignment, said predetermined plane and the plane defined by the running tool mandrel axis and the radial bore therein being angularly related relative to one another at an angle corresponding to the pre-

terminated angle of the selected one of said tubing mandrels.

7. A well installation comprising a tubing string, a plurality of tubing mandrels connected at predetermined elevations in said tubing string, each of said tubing mandrels having aligned upper and lower necks and a main bore extending between said necks, means forming an open topped, well tool receiving pocket within said offset mandrel, said pocket having its longitudinal axis offset from said main bore, a guide shoe comprising a cylindrical sleeve mounted in said upper neck coaxially therewith, said sleeve having a longitudinal slot extending from the upper surface to the lower end thereof, the vertical plane determined by said slot and the main bore axis and the vertical plane determined by said offset pocket axis and said main bore axis being angularly related relative to one another by a predetermined angle and wherein said predetermined angle is different for each of said tubing mandrels, a plurality of running tools each comprising an elongated mandrel adapted to pass longitudinally through the sleeves of said tubing mandrels, a locator key projecting radially outwardly from said running tool mandrel and adapted to fit within said sleeve slots, an elongated connector member, means connecting the upper end of said connector member to the lower end of said running tool mandrel for pivotal movement of said connector member relative to said running tool mandrel in a single predetermined plane which includes the axis of said running tool mandrel, means on the lower end of said connector member for releasably engaging a well tool, said running tool mandrel and connector member having their axes in alignment at one relative position therebetween, and spring means acting between said running tool mandrel and connector member for normally biasing said connector member to pivot about said running tool mandrel in said predetermined plane to a position wherein said running tool mandrel and connector member axes are out of alignment, said predetermined plane and the plane defined by the running tool mandrel axis and the radial bore therein being angularly related relative to one another by a predetermined angle, said last predetermined angle being different for each of said running tool mandrels and wherein one each of said running tools has its said predetermined angle equal to the predetermined angle of one each of said predetermined angles of said tubing mandrels.

8. A well installation as set forth in claim 7 wherein the upper surface of each of said sleeves slopes upwardly from each side of the slot therethrough.

9. A well installation comprising a tubing string, a plurality of tubing mandrels connected at predetermined elevations in said tubing string, each tubing mandrel having a vertical main bore extending therethrough, means forming an open topped, well tool receiving pocket within said tubing mandrel, said pocket having its longitudinal axis offset from said main bore, a guide shoe comprising a cylindrical sleeve mounted in the upper end of said bore coaxially therewith, said sleeve having a longitudinal slot extending from the upper surface to the lower end thereof, said sleeve having its upper surface sloping upwardly from each side of said slot, the vertical plane determined by said slot and the main bore axis and the vertical plane determined by said offset pocket axis and said main bore axis being angularly related relative to one another by a predetermined angle and wherein said predetermined angle is different for each of said tubing mandrels, a plurality of running tools each comprising an elongated mandrel adapted to pass longitudinally through the sleeves of said tubing mandrels and having a radial bore therein, a locator key disposed in said radial bore, spring means for urging said key radially outwardly from said running

tool mandrel, said key having an outer vertical flange adapted to fit within said sleeve slot, said flange having a downwardly and outwardly sloping upper surface, an elongated connector member, means connecting the upper end of said connector member to the lower end of said running tool mandrel for pivotal movement of said connector member relative to said running tool mandrel in a single predetermined plane which includes the axis of said running tool mandrel, means on the lower end of said connector member for releasably engaging a well tool, said running tool mandrel and connector member having their axes in alignment at one relative position therebetween, and spring means acting between said running tool mandrel and connector member for normally biasing said connector member to pivot about said running tool mandrel in said predetermined plane to a position wherein said running tool mandrel and connector member axes are out of alignment, said predetermined plane and the plane defined by the running tool mandrel axis and the radial bore therein being angularly related relative to one another by a predetermined angle, said last predetermined angle being different for each of said running tool mandrels and wherein one each of said running tools has its said predetermined angle equal to the predetermined angle of one each of said predetermined angles of said tubing mandrels.

10. A running tool comprising an elongated mandrel having a radial bore therein, a locator key disposed in said radial bore, spring means for urging said key radially outwardly from said mandrel, said key having a downwardly and outwardly sloping upper surface, an elongated connector member, means connecting the upper end of said connector member to the lower end of said running tool mandrel for pivotal movement of said connector member relative to said mandrel in a single predetermined plane which includes the axis of said mandrel, means on the lower end of said connector member for releasably engaging a well tool, said mandrel and connector member having their axes in alignment at one relative position therebetween, and spring means acting between said mandrel and connector member for normally biasing said connector member to pivot about said mandrel to a position in said predetermined plane wherein said mandrel and connector member axes are out of alignment, said predetermined plane and the plane defined by the mandrel axis and the radial bore therein being angularly related relative to each other by a predetermined angle.

11. A running tool comprising an elongated mandrel, a locator key extending radially outwardly from said mandrel, an elongated connector member, means connecting the upper end of said connector member to the lower end of said running tool mandrel for pivotal movement of said connector member relative to said mandrel in a single predetermined plane which includes the axis of said mandrel, said mandrel and connector member having their axes in alignment at one relative position therebetween, and spring means in engagement with said mandrel and connector member for normally biasing said connector member to pivot about said mandrel to a position in said predetermined plane wherein said mandrel and connector member axes are out of alignment, said predetermined plane and the plane defined by the running tool mandrel axis and the radial key being angularly related relative to each other by a predetermined angle.
